CLAIM

The ornamental design for a display for mobile phone, as shown and described.

DESCRIPTION

FIG. 1 is a front, right side perspective view of a display for mobile phone showing my new design;
 FIG. 2 is a rear, left side perspective view thereof;
 FIG. 3 is a front elevation view thereof;
 FIG. 4 is a rear elevation view thereof;
 FIG. 5 is an enlarged left side elevation view thereof;
 FIG. 6 is an enlarged right side elevation view thereof;
 FIG. 7 is a top plan view thereof; and,
 FIG. 8 is a bottom plan view thereof.
 The broken lines in the drawings illustrate portions of the display for mobile phone that form no part of the claimed design.
